US00D508628S

(12) **United States Design Patent** (10) Patent No.: **US D508,628 S**
Crawford et al. (45) Date of Patent: **** Aug. 23, 2005**

(54) **ADJUSTABLE DUMBBELL SUPPORT BASE**

(75) Inventors: **Douglas A. Crawford**, Lafayette, CO (US); **Eric D. Golesh**, Thornton, CO (US); **Edward L. Flick**, Denver, CO (US); **Matthew Rauwerdink**, Westminster, CO (US)

(73) Assignee: **Nautilus, Inc.**, Vancouver, WA (US)

(**) Term: **14 Years**

(21) Appl. No.: **29/164,931**

(22) Filed: **Jul. 31, 2002**

(51) LOC (8) Cl. **08-08**

(52) U.S. Cl. **D6/552**

(58) Field of Search **D6/552; D21/691, D21/662, 686, 690; 482/104, 148; 211/85**

Primary Examiner—Brian N Vinson

(74) Attorney, Agent, or Firm—Dorsey & Whitney LLP

(57) **CLAIM**

The ornamental design for an adjustable dumbbell support base, as shown and described.

DESCRIPTION

FIG. 1 is a perspective view of the adjustable dumbbell support base of the present invention;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.
